UNITED STATES PATENT OFFICE.

GEORGE H. HARRIS, OF SYRACUSE, NEW YORK.

INTERNAL-COMBUSTION ENGINE.

1,096,505.

Specification of Letters Patent. Patented May 12, 1914.

Application filed December 5, 1912. Serial No. 735,074.

To all whom it may concern:

Be it known that I, GEORGE H. HARRIS, a citizen of the United States, residing at Syracuse, in the county of Onondaga and State of New York, have invented certain new and useful Improvements in Internal-Combustion Engines, of which the following is a specification.

This invention relates to improvements in internal combustion engines, and has for its object to provide a novel, simple and effective valve mechanism, wherein a one-part valve of the piston type controls both the intake and exhaust.

15 A further object is to provide a valve for engines of the class which is arranged to receive and hold the compression charge until the explosion occurs.

A further object is to provide a valve-
20 gear which is continuously rotated by the main crank-shaft, and other co-operative parts which are arranged to move the valve intermittently for controlling the admission of the live gas, the compression of said gas, 25 and the exhaust of the dead or burnt gas, the step by step movements of the valve taking place at regular intervals corresponding to the working of the engine.

A further object is to provide means for
30 completely freeing the cylinder of burned gases after each explosion, thereby lessening the danger of back-firing, and also preventing the accumulation of free carbon within the working cylinder.

35 The features and parts of the invention will be understood from the detailed description which follows, and by reference to the accompanying drawing which forms a part of the specification, and in which--

40 Figure 1 is a central vertical section through a four cycle engine; showing the valve positioned for the admission of the explosive gas. Fig. 2 is a similar section; showing the valve in position to receive the charge when compressed. Fig. 3 is a similar section; showing the position of the valve and piston at the end of a compression stroke. Fig. 4 is a similar section; showing the valve in the exhaust position; 50 also showing by full and dotted lines the positions of the piston and cam during the exhaust stroke.

Similar characters of reference are assigned to corresponding parts throughout the several views:

In the drawings, 2 represents the crank case or base, 3 the crank-shaft, and 4 the crank of the engine.

5 represents the main cylinder, any number of which may be mounted on base 2. 60

6 represents the piston, and 7 the rod which connects the piston with the crank 4.

The cylinder 5 is open at the bottom, and closed at the top 8, and is preferably ribbed at 9 for air-cooling the top. The cylinder 65 may be cooled by any suitable means, as by water, by means of a jacket 10.

11 represents a port, which is employed for both the intake and the exhaust. The port 11 may be fashioned in any suitable 70 manner, but preferably comprises a slot, which is preferably disposed at the upper end and at one side of the cylinder 5.

12 represents a threaded opening in the head 8 to receive the usual spark-plug or 75 igniter (not shown).

In the present invention, the intake and exhaust for the engine is handled by an auxiliary cylinder 13, which is preferably cast integrally with the main cylinder 5. The cylinder 13 has a reduced opening 14 at its top to receive the explosive mixture. Both intake and exhaust are controlled by a hollow piston valve 15, comprising a cylinder which is reciprocatably disposed in the cylindrical part 13. The valve 15 is provided with a port 16 which is disposed near its upper end and faces the main cylinder. The valve casing 13 is considerably longer than the valve 15 and extends above the cylinder 5, so that the latter may be moved upwardly a sufficient distance to bring the port 16 opposite the port 11, and at the same time shut off communication of said port with the intake 14. 90 95

17 represents an exhaust port which is disposed near the bottom and at the opposite side of the valve 15, and this port is adapted to register with a port 18 of the casing 13 when the valve is in its extreme 100 upper or exhaust position. The valve 15 is closed at its upper and lower ends, and is operated vertically by means of a rod 19, which is preferably screwed into a threaded opening in the bottom of the valve. The bottom of the valve casing 13 is closed by a cap 20, which is perforated centrally and serves as a guide for the upper end of the rod 19. The valve 15 is operated upwardly by means of a cam 21, which is mounted 110

upon a shaft 22, which parallels the main shaft 3. The cam shaft 22 is preferably rotated by the main shaft 3, by means of spur-gears 23 and 24, the gear 23 being mounted upon the main shaft, while the gear 24 is mounted upon the cam shaft. Where my improved valve is applied to a two-cycle engine, the driving gear 23 is preferably one-half the size of the driven gear 24. Under 10 this arrangement the main shaft rotates twice while the cam shaft rotates once. The cam 21 is preferably a 3-step-cam, which is so arranged as to impart intermittent upward movements to the valve 15, which assumes three distinct positions during each 15 intake, explosion and exhaust.

Fig. 1 shows the valve in its lowermost or intake position. Fig. 2 shows the valve in its intermediate or compression and firing position. And Fig. 4 shows the valve in the highest or exhaust position. As explained, the cam 21 is only employed for raising the valve intermittently from the lowest to the highest position. To return the valve from 20 the exhaust to the intake position, I provide a coil spring 25 which surrounds the rod 19, the upper end of the spring bearing against the underside of the cap 20, while the lower end of the spring engages a washer or stop 26 which is held in place by a pin 27. The lower middle portion of rod 19 is supported and is guided by a cylindrical bushing 28 which pierces the top of the case 2. The upper end of the bushing is counterbored to 30 receive the spring 25.

The operation of my improved engine is as follows: Referring first to Fig. 1, the valve 15 is in its lowest position, the lower end of the valve rod 19 is in engagement with the 40 first step of the cam, and the piston 6 in its highest position. There is now a free passage for the live gas from the intake chamber 14' to the main cylinder 5 by way of the port 11. The first downward movement of the piston 5 draws the charge of the live gas 45 into the main cylinder. By the time the piston 6 reaches the lower end of its stroke, (see Fig. 2) the cam 21 will have moved one-quarter of a turn, and the lower end of the 50 valve-rod 19 moves from the first to the second step of the cam, which forces the valve 15 upwardly and brings the upper end of the port 16 opposite the port 11, and at the same time the upper end of the valve 55 cuts off the passage to the intake chamber 14'. The valve will then remain in the latter position while the piston 6 makes the next up and down strokes. The next upward movement of the piston forces the 60 charge of the new gas out of the cylinder 5 through the ports 11 and 16, and compresses the said charge in the valve 15 (see Fig. 3). The capacity of the hollow valve 15 should be about one-third that of the main cylinder, 65 which allows the explosive charge to be ade-

quately compressed. Just as the piston approaches the end of the compression stroke, the explosion takes place, and drives the piston down again from the position shown in Fig. 3, to that shown in full lines in Fig. 4. 70 During the downward stroke of the piston under the force of the explosion, the cam 21 is operated substantially another one-quarter turn, and at the end of this movement the rod 19 moves on the third step 21' of the 75 cam, which lifts the valve 15 to its third or highest position, which brings the bottom of the port 16 opposite the port 11, and at the same time the port opening 17 is brought opposite the port 18. Owing to the arrangement of the cam surface 21', the valve 15 will remain in its uppermost position while the piston moves upwardly for completing the second upstroke, and by this last upward movement the piston forces all of the dead 80 gas out of the cylinder 5 into the valve 15, from which it exhausts in a ready manner through the ports 17 and 18. When the piston 6 reaches the dotted line position, the cam 21 also will have moved to the dotted 85 line position, shown in Fig. 4, and then the valve 15 will suddenly drop by its own weight, aided by the power of the spring 25, to its lowermost or starting position, as shown in Fig. 1. This latter operation of 90 the valve 15 cuts off the exhaust opening 18 and reopens the port 11 for the passage of the new gas from chamber 14' into the cylinder 5. The arrangement of the cam is such that the gravitating movement of the valve 100 is accomplished instantaneously at the end of the exhaust stroke and before the piston has time to start downwardly on its suction stroke. Owing to the arrangement of the valve 15, which suddenly drops from the 105 third to the first position at the end of each exhaust stroke, whatever burned gas still remains in the valve is shut entirely off, and the incoming new mixture enters a comparatively clear and clean cylinder. The new 110 gas having a temperature much lower than the cylinder tends to exert a desirable cooling effect, which would not be the case if the new gas became mixed with the hot burnt gas at each intake.

Heretofore, the makers and users of internal combustion engines have experienced a good deal of trouble, on account of the failure to entirely free the cylinder from dead or burnt gases after each explosion. The 120 presence of hot dead gas in the cylinders at the time the new gas enters, not only weakens the explosive mixture, which results in loss of power, but there is a constant danger of the new charge exploding prematurely. 125 In the present invention, I have entirely eliminated these dangers, by utilizing the exhaust stroke of the piston for forcing all of the dead gases from the cylinder into the hollow valve, and then by providing for 130

completely isolating the said gases during the intake, which is accomplished by the breaking of the communication of the ports 11 and 16. Furthermore, where considerable burned gas is allowed to remain in the cylinder after each working stroke of the piston, more or less free carbon is deposited on the top and side walls of the cylinder which are not reached by the piston. This accumulation of free carbon generally takes place immediately after the starting of the engine and before the engine becomes heated sufficiently to effect complete combustion. Afterward, when the engine gets hot, this free carbon ignites and burns to ashes, and most of the ashes pass off with the exhaust. It often happens however, that some of the ashes work downwardly between the piston and cylinder and score and otherwise injure these parts. In the present device this latter trouble is almost entirely obviated, first, by driving practically all of the dead gases out of the cylinder, as described, and second, by allowing the piston at each upward stroke to travel to within approximately one-eighth of an inch of the head 8, which insures the self-cleaning of the sides of the cylinder, and thus prevents the accumulation of enough free carbon to cause any trouble, even though the engine is operating at a low temperature.

The valve gearing herein shown and described is extremely simple and it is positive in its actions. It is practically noiseless, and is very effective in its operation.

The provision of the hollow piston valve comprising but a single part, which serves as the compression chamber for holding the charge until it is exploded, obviates the necessity for the usual cams, springs and other valve-operating parts usually employed for controlling the admission and the exhaust of explosive engines of the class. Furthermore, by providing for the compression of the explosive gas inside the valve instead of in the main cylinder, and by utilizing the large hollow interior of the valve for the passage of the exhaust, the space between the piston and the cylinder-head is reduced to a small fraction of an inch, thus allowing the cylinder to be freed of all of the burned or dead gases at the end of each exhaust stroke. The valve is also perfectly balanced and requires very little power to operate it. The timing of the valve movements, whether effected by the cam or by the spring, is positive and accurate, and permits the admission and exhaust to take place at exact predetermined intervals with the desired effectiveness. The valve and its operating mechanism are so simple and positive that little or no adjustment of the parts is required once they are assembled ready for operation, and there is less danger of any of the parts becoming disarranged during the

working of the engine, than in any other style of engines known to me.

Having thus described my invention, what I claim as new and desire to secure by Letters Patent, is—

1. In an internal combustion engine, the combination of a cylinder, a piston in said cylinder, a valve chamber arranged adjacent said cylinder and connected thereto by a port, a hollow reciprocating valve in said chamber for controlling the admission and exhaust, said valve having an opening communicating with said port, a valve gear comprising a cam and a rod for operating said valve in one direction intermittently for positioning the opening in said valve for receiving the gas to be compressed and also the burned gas to be exhausted, and a spring adapted to aid the gravitation of said valve in the opposite direction. 75

2. In an internal combustion engine, the combination of a cylinder, a valve chamber arranged adjacent said cylinder and connected thereto by a port, a hollow reciprocating valve in said chamber for controlling the admission and exhaust, said valve having an opening adapted to register with said port, a valve gear comprising a cam and a rod for operating said valve in one direction intermittently for positioning the opening 90 in said valve for receiving the gas to be compressed and also the burnt gas to be exhausted, and means coöperating with said cam for effecting the gravitation of said valve in the opposite direction. 10

3. In an internal combustion engine, the combination of a cylinder, a valve chamber arranged parallel to said cylinder, a hollow reciprocating valve for controlling the admission and exhaust of gases to and from the said cylinder, means for positioning said valve for allowing explosive gas to enter said cylinder, means for positioning said valve for allowing said gas to be compressed within the valve, means for positioning said valve so as to allow the burnt gases to be forced from said cylinder back into said valve for exhausting said gas, and means for restoring said valve to the first position ready for a subsequent charge of the explosive gas. 11

4. In an internal combustion engine, the combination of a cylinder, a piston in said cylinder, a crank-shaft for operating said piston, a valve chamber adjacent and parallel to said cylinder and connected thereto by a port, a hollow piston valve in said chamber adapted to be held by gravity below the said port for permitting the passage of live gas from said chamber to said cylinder, a valve-gear comprising a cam driven by the crank-shaft and a rod connected to the valve adapted to lift the valve intermittently for bringing the valve into position to receive the compression charge, and also to receive 125 130

the exhaust from the cylinder after each explosion, and means for effecting the gravitating of the valve to its position below said port.

- 5 5. The combination of a cylinder, a piston in said cylinder, a hollow reciprocating valve controlling the admission and exhaust of the gases to and from the cylinder, said valve having a port facing the cylinder and an exhaust port in its opposite side, a chamber for said valve arranged adjacent the cylinder and connected thereto by a port, said chamber having an intake opening at its top and an exhaust opening near its bottom, a valve-
10 gear for operating said valve upwardly step by step for permitting the compression of the live gas within said valve in advance of the explosion, and for permitting the dead gases to be forced back into said valve after
15 the explosion, for scavenging the cylinder; and means for effecting the gravitating of said valve from its uppermost position to its lowermost position for the admission of a new charge of live gas.
- 20 6. In an internal combustion engine, the combination of a cylinder, a piston in said cylinder, a crank-shaft for operating said piston, a valve chamber adjacent and parallel to said cylinder and connected thereto
25 by a port, a hollow piston valve in said chamber adapted to be held by gravity below the said port for permitting the passage of live gas from said chamber to said cylinder, a valve-gear comprising a cam driven
30 by said crank-shaft and a rod connecting with said valve adapted to lift said valve intermittently for first cutting off the admission and allowing the piston to compress the live gas within said valve, and then for permitting the piston to force the dead gas back
35 into said valve for scavenging the cylinder, and means for moving said valve to its lowermost position for reopening the said port for the admission of the live gas.
- 40 7. The combination of a cylinder, a piston in said cylinder, a valve chamber adjacent said cylinder and connected thereto by a port, a hollow reciprocating valve in said chamber, said valve adapted to be held by
45 gravity in position to allow live gas to pass from said chamber into said cylinder, a cam adapted to raise said valve for cutting off the admission and for allowing the piston to compress said gas within the valve, said cam
50 adapted to raise said valve a second time for permitting the dead gas to be forced back

into said valve for scavenging the cylinder, and means for effecting the gravitation of said valve to the first position ready for a subsequent admission.

60 8. A cylinder, a valve chamber connected to said cylinder by a port, said chamber having an intake opening in its top and an exhaust opening near its bottom, a hollow reciprocating valve in said chamber having an opening adapted to connect with said port and having an outlet opening adapted to register with said exhaust opening, means for moving said valve in said chamber for allowing explosive gas to pass from said chamber to said cylinder, means for moving said valve to bring one of its openings opposite said port to permit the compression of said gas within said valve, and means for moving said valve for permitting the burnt gases to pass through the valve and through said outlet and exhaust openings.

65 9. In an internal combustion engine, a cylinder, a piston in said cylinder, means for operating said piston, a valve chamber connecting to said cylinder by a port, a hollow piston valve in said chamber adapted to be held by gravity below said port for allowing live gas to pass from said chamber into said cylinder, means for raising said valve at the end of the suction stroke for bringing the valve into position to receive the compression charge, means for raising said valve a second time at the end of the explosion stroke for permitting the exhaust to pass through said valve and said chamber, and means for lowering said valve at the end of the exhaust stroke for restoring said valve to its position below said port.

70 10. A valve mechanism for controlling the admission and exhaust of an engine, comprising a cylindrical valve chamber, a hollow piston valve moveable in said chamber, said valve having a port facing the cylinder of the engine, a valve-gear comprising a cam 100 and a rod for operating said valve in one direction for positioning the port in said valve for receiving first the gas to be compressed and then the burnt gas during the exhaust, and means for operating said valve in the opposite direction by a single movement.

In testimony whereof I affix my signature in presence of two witnesses.
